UNITED STATES PATENT OFFICE

JEREMIAH HOWARD, OF NEW YORK, N. Y.

IMPROVEMENT IN MILLS FOR SUGAR-CANE.

Specification forming part of Letters Patent No. 21,340, dated August 31, 1858.

To all whom it may concern:

Be it known that I, JEREMIAH HOWARD, of the city, county, and State of New York, have invented a new and useful Improvement in Mills for Crushing Sugar-Cane and other Substances; and I do hereby declare that the following is a full, clear, and exact description of the same, reference being had to the annexed drawings, making a part of this specification, in which—

Figure 1 is an end view of a mill with my invention applied to it, a portion of the latter being bisected, as indicated by the line $x-x$, Fig. 3. Fig. 2 is a transverse central section of the same. Fig. 3 is a plan or top view of the same.

Similar letters of reference indicate corresponding parts in the several figures.

This invention consists in applying, by suitable means, hydraulic pressure to the lower rollers of a crushing-mill, so that the rollers will be allowed to yield or give, and the space between them and the upper roller regulated according to the work to be performed, or, in other words, according to the layer of stuff that is fed and crushed between them, thereby insuring the mill against fracture, and causing it to work much more efficiently than usual.

To enable those skilled in the art to fully understand and construct my invention, I will proceed to describe it.

A A' A'' are three cast-iron rollers, which are fitted between or have their bearings a a' in heads B, which are attached to a suitable base or bed, C. The rollers are constructed and arranged in the usual way, or in a way common to sugar-cane mills, the two lower rollers, A A'', being in the same horizontal plane, with a space between them, and the upper roller, A', directly over the space between the lower rollers. The journals of the upper roller, A', are fitted in permanent bearings a' , and the bearings a'' of the roller A'' may be regulated by set-screws b , so as to regulate the space between it and the upper roller, A', as occasion may require. The bearings a , however, of the roller A have the rods c of pistons D bearing against them, (see Fig. 1,) said pistons being fitted in cylinders E E', which are attached to, and may be cast with, the heads B B' of the mill.

F is a reservoir containing water, and G is a force-pump connected therewith. H is a pipe which communicates with the pump G, said pipe being connected with a pipe, I, the ends of which communicate with the cylinders E E'. A portion of the pipe I passes through the reservoir F, and to the portion of the pipe within the reservoir a loaded valve, J, is attached, the arm or lever d of the valve J, to which the valve is attached, being provided with a sliding weight, e.

The pump G may be operated from any proper working part of the device, either from the driving-shaft or otherwise. In the drawings it is shown as being operated from the shaft or one of the journals a^x of the upper roller, A', by a connecting-rod, K, attached eccentrically to the end of the journal a^x .

The three rollers are all connected at one end by gear-wheels L L L, as shown plainly in Fig. 3.

The operation is as follows: Motion is given the upper roller, A', in any proper way, and the sugar-cane or other substance to be crushed is fed down between the rollers A' A'', the latter being adjusted at a proper distance from the former by regulating or turning the screws b b . The substance is crushed in passing between the rollers A' A'', and the juice is expressed therefrom as it passes between the rollers A' A'', the latter rollers working quite close together, so that the substance will be subjected to a sufficient pressure, which is produced by the pump G forcing water from the reservoir F into the cylinders E, the pistons D being acted upon by the pressure of the water, and the rods c acting directly on the bearings a . The pressure of the water on the pistons D will be constant under an equal speed of the rollers and a certain adjustment of the weight e , so as to allow a proper escape through the valve J, and in case the substance operated upon passes between the rollers A' A'' in a layer of unequal thickness, which is always the case to a greater or less extent, the roller A is allowed to recede, the valve J being momentarily opened to a farther degree in order to allow the proper volume of water to escape. The pressure of roller A may be graduated as desired by adjusting the weight e of valve J, and the pressure will always be

commensurate with the work to be performed, none of the working parts of the mill being subjected to any undue strain.

I do not confine myself to the precise form of valve J, nor to the specific arrangement of parts herein shown and described, for the parts may be differently constructed and disposed and still the same effect obtained by substantially the same means.

I would remark that although the invention is shown applied to only one roller, A, still it may, if desired, be applied to both rollers A'A".

Having thus described my invention, what

I claim as new, and desire to secure by Letters Patent, is—

The employment or use of a pump, G, water-reservoir F, and valve J, in connection with necessary pipes H I and cylinders E, provided with pistons D, acting on the bearing of the roller or rollers, the whole being arranged as shown, or in any equivalent way, so as to operate as and for the purpose set forth.

JEREMIAH HOWARD.
